UNITED STATES PATENT OFFICE

2,502,052

WATER RECIRCULATING SYSTEM FOR
SWIMMING POOLS

Everett W. Landon, San Mateo, and David K. Cavenah, North Hollywood, Calif., assignors to Landon Standard Pools, Burlingame, Calif.

Application November 21, 1947, Serial No. 787,350

2 Claims. (Cl. 210—11)

1

This invention relates to new and useful improvements and structural refinements in swimming pools, and the principal object of the invention is to provide a swimming pool equipped with what may be called a water recirculating system which will facilitate repeated use of the water in the pool with a minimum amount of waste, and which, at the same time, will skim foreign matter from the water so that the water remains in a sanitary condition for bathing for considerable periods of time.

A further object of the invention is to provide a recirculating system for swimming pools which also includes a chemical filtering unit and which, by virtue of this and above described characteristics, will enable the pool to remain in a thoroughly sanitary condition for a period of three or four weeks, without attention such as draining or skimming at frequent intervals which is necessary in pools of conventional types.

Another object of the invention is to provide a water recirculating system for swimming pools which also includes means for maintaining the water in the pool at a constant, predetermined level.

An additional object of the invention is to provide a recirculating system of the character described which is simple in construction, which may be easily installed, and which, as aforesaid, will function for considerable periods of time without attention.

A still further object of the invention is to provide a recirculating system which, however, may be quickly and easily inspected or cleaned, when this form of servicing occasionally becomes necessary.

With the above more important objects in view, and such other objects as may become apparent as this specification proceeds, the invention consists essentially of the arrangement and construction of parts as illustrated in the accompanying drawings, in which:

Figure 1 is a top plan view of a swimming pool constructed in accordance with the teachings of the invention;

Figure 2 is a cross sectional view, taken substantially in the plane of the line 2—2 in Figure 1;

Figure 3 is a top plan view of an overflow tank and connections used in the invention;

Figure 4 is an elevational view, taken in the direction of the arrow 4 in Figure 3; and

Figure 5 is a combined cross sectional view, taken substantially in the plane of the line 5—5

2

in Figure 1 and an elevational view of a filtering unit used in the invention.

Like characters of reference are employed to designate like parts in the specification and throughout the several views.

Referring now to the accompanying drawings in detail, the invention is adapted for use in association with a swimming pool 10 of suitable design, the same including perimetric walls 11 and a sloping bottom 12, as will be clearly understood.

The bottom 12 is provided with the usual drain 13 which communicates with a pipe 14, hereinafter referred to.

15 The pool is equipped in the perimetric walls 11 thereof with a plurality of water inlets 15, hereinafter more fully described, and also with a water outlet 16.

16 The outlet 16 assumes the form of a tube 17 20 embedded in the wall 11 and formed with a longitudinally extending slot 18, this slot communicating with the pool through the medium of an elongated opening 19 formed in the pool walls. Needless to say, the water in the pool is maintained at a predetermined, normal level 20, and it should be observed that the opening 19 and the tubes 15 are disposed substantially at this level, as is best shown in Figure 5.

An overflow tank 21 is provided below the ground level 22, this tank comprising a suitable receptacle formed with an extension neck 23, the upper surface of which is flush with the ground level and is equipped with a "hand-hole" cover 24 whereby access may be had to the tank for purposes of inspection or cleaning.

25 A baffle plate 25, formed with a plurality of openings 26, is positioned in the tank 21 which is separated thereby into a suction chamber 27 and an equalizing chamber 28, the baffle plate 25 being vertically disposed, as will be clearly apparent from the accompanying Figure 5.

The aforementioned outlet tube 17 is connected by means of a pipe 29 to the suction chamber 27 of the tank 21, while a conduit 30 connects 45 the equalizing chamber 28 with the pool, for purposes hereinafter to be more fully described. It will be noted that the conduit 30 is disposed somewhat below the normal level 20 of the water in the pool.

50 An overflow tube 31 is also provided on the tank 21, the tube 31 communicating with the upper end portion of the suction chamber 27. Moreover, a suction line 32 enters the suction chamber 27 and is provided with a downturned elbow 33, the line 32 communicating with the

intake of a suitable water pump 34, which is preferably mounted a convenient location below the ground level. A suitable strainer assembly 35 may be installed in the line 32 for obvious reasons, and the outlet of the pump 34 is connected by means of a delivery line 36 to a filtering unit 37 of conventional type. This unit includes the usual filtering tank 38, hypochlorinator 39, chlorine tank 40, etc., the entire filtering unit being, as aforesaid, of conventional type so that further description thereof at this point is deemed unnecessary.

The unit 37 also includes a waste disposal line 41 and a filtered water delivery line 42, the latter communicating with the various water inlets 15, as is best shown in Figure 1.

These inlets, rather than simply entering the pool at right angles to the inner surface of the walls 11, are angularly disposed, so to speak, so that the water discharged therefrom will be diverted in the direction of the arrows 43 and circulation, so to speak, of the water in the pool will be produced, as indicated at 44.

By virtue of this angular deflection of the inlets, two forms of water circulation will, in fact, be created, the primary circulation being that on the water level 20 which provides a movement of leaves, lint, and other major foreign matter toward the perimetric walls 11 of the pool, and hence, into the overflow tank 21.

A secondary circulation is also created, this taking place intermediate the depth of the pool and involving relatively smaller but heavier particles of foreign matter which absorb water and remain in suspension, so to speak, for some period of time, during which they become heavier and eventually settle on the floor or bottom of the pool as the secondary circulation takes place.

Water from the bottom of the pool is recirculated through the pump 34 and filter unit 37 through the pipe 14 which communicates by means of a T-coupling 14 with the suction line 32. When so desired, the pool may be emptied through the drain 13 by means of the pump 34, or alternatively, a direct outlet may be associated with the drain 13.

The overflow entering the tube 17 is delivered to the suction chamber 27 of the tank 21 by the sucking action of the pump 34 which tends to exhaust the contents of the suction chamber by delivering them to the filtering unit 37. By virtue of this sucking action of the pump, the level of water in the chamber 27 will be normally below the water level 20, and as a result, the water in the pool will tend to overflow into the chamber 27 under the influence of gravity. As will be clearly understood, after passing through the filtering unit 37, the filtered water is delivered through the lines 42 and inlets 15 to the swimming pool, as has already been explained.

The primary purpose of the conduit 30 is to maintain the equalizing chamber 28 full of water, whereby the suction chamber 27 will be maintained in a similar condition by virtue of the openings 26. In this manner, the pump 34 will be prevented from sucking air when, for some reason, the overflow of water through the tubes

17, 29 is temporarily discontinued. If desired, the openings 26 may be temporarily "blocked" or stoppered by any suitable means, so as to regulate the flow of water from the chamber 28 to the chamber 27, depending upon the overflow of water through the tubes 17, 29.

The overflow tube 31 carries "waste" and automatically assures that the water level in the tank 21 and in the pool 10 is maintained at the predetermined, normal level.

It is believed that the advantages and use of the invention will be clearly apparent from the foregoing disclosure, and accordingly, further description thereof at this point is deemed unnecessary.

Having described the invention, what is claimed as new is:

1. In combination with a swimming pool, a water recirculating system comprising a pump having an inlet and an outlet, a filter connected to the outlet of said pump, a coupling on the inlet of said pump, an effluent conduit extending from the bottom of said pool to said coupling, an influent conduit extending from said filter and communicating with said pool, an equalizing tank, an overflow tube extending from said tank and communicating with said pool at a point spaced downwardly from the upper edge of the latter, and a suction pipe connecting said tank to said coupling.

2. In combination with a swimming pool, a water recirculating system comprising a pump having an inlet and an outlet, a filter connected to the outlet of said pump, a coupling on the inlet of said pump, an effluent conduit extending from the bottom of said pool to said coupling, an influent conduit extending from said filter and communicating with said pool, an equalizing tank and a partition therein separating the same into juxtaposed overflow and suction chambers, an overflow tube extending from said suction chamber and communicating with said pool at a point spaced downwardly from the upper edge of the latter, a suction pipe connecting said suction chamber to said coupling, said partition being provided with an opening for controlling the rate of water flow from said equalizing chamber to said suction chamber, and an equalizing conduit extending from the equalizing chamber and communicating with said pool at a point substantially below said overflow tube.
